S. A. ASQUITH.

AIR HOSE SUPPORT.

APPLICATION FILED FEB. 10, 1920.

1,374,803.

Patented Apr. 12, 1921.

UNITED STATES PATENT OFFICE.

STEAD A. ASQUITH, OF WATERLOO, IOWA.

AIR-HOSE SUPPORT.

1,374,803.

Specification of Letters Patent.

Patented Apr. 12, 1921.

Application filed February 10, 1920. Serial No. 357,669.

To all whom it may concern:

Be it known that I, STEAD A. ASQUITH, a citizen of the United States, residing at Waterloo, in the county of Blackhawk and 5 State of Iowa, have invented certain new and useful Improvements in Air-Hose Supports, of which the following is a specification.

This invention relates to an air hose support and has for its principal object the production of a support which will normally hold the air hose directly over the center of the automobile thus keeping it off the ground and will at the same time allow easy 15 access for applying the hose to either side of the car.

Another object of the invention is to provide a support which will normally be in a position so as to hold the hose in an inoperative position.

A still further object of the invention is to provide means whereby the support will only operate so as to allow the use of the hose when a coin is inserted into a coin receiving mechanism provided in the support.

With these and other objects in view, this invention consists of certain novel arrangements, constructions and combinations of parts, as will be hereinafter more fully described.

In the accompanying drawing:—

Figure 1 is a side elevation of the preferred form of my invention.

Fig. 2 is a fragmentary vertical section 35 taken through the upper portion of the post showing the locking mechanism for the lever.

Fig. 3 is a fragmentary vertical section 40 taken through the lower portion of the post showing the coin receiving mechanism.

Fig. 4 is a section taken at right angles to the view shown in Fig. 3.

Fig. 5 is a section taken through the end 45 of the hose supporting lever, and

Fig. 6 is a slightly modified view of my invention.

Referring to the accompanying drawing by numerals, it will be seen that 1 designates a hollow post which is vertically situated 50 upon the ground and will be usually situated along the curb or side of the road adjacent the garage. This post 1 has situated at its top a collar 2 which has extended vertically therefrom the standards 3 which are 55 diametrically opposed and parallel to each other. A lever 5 which is also hollow is

pivotaly mounted between the standards 3 by means of the bolt and nut 4. The lever 5 is provided with the handle 6 which has at its extremity the weight or ball 7 which will normally hold the lever in the position shown in Fig. 1. At the other extremity of the lever 5 there is provided the hook portion 8 which is provided with a slot 9 for a purpose to be hereinafter set forth. 65

A hose 10 having a tire attachment 11 extends to a compressed air tank and passes a short distance from the post 1 and then extends into the lever 5 around the hook portion 8. When it is desired to use the hose 70 it will be seen that the lever 5 will take the position shown in dotted lines in Fig. 1 so that the hook 8 will be positioned over the center of the automobile and the hose attaching means 11 may be used to attach the hose 75 to the tire for inserting air therein.

Adjacent the fulcrum of the lever 5 is situated the arcuate guide plate 12 which has a notch therein for receiving the latch 14 which is pivoted at 14 and attached to the 80 bar 15. The latch 13 when inserted in the notch in the plate 12 will normally hold the lever 5 in the position shown in Figs. 1 and 2 thereby preventing the use of the hose 10 by an autoist. 85

The bar 15 extends down through the post 1 and is provided with a coin receiving finger 16 for receiving the coin 17 which will be passed through the slot 18. When the coin is in the position shown in Fig. 3 it will 90 be seen that the bell crank lever 19 may be actuated so as to pull downwardly upon the bar 15 thereby releasing the latch 14 which will allow the lever 5 to take the position shown in dotted lines in Fig. 1. 95

The modification shown in Fig. 6 is of practically the same construction as the preferred embodiment of my invention just described. This modification consists of a device which may be attached to the side of a 100 wall when so desired or on front of a garage so as to extend outwardly, 21 being directly over curb. It consists of the pipe 20 which extends at right angles to the wall 22 and has the upwardly extending portion 21 connected thereto by means of an L. The rest of the construction is the same as the construction described in my preferred modification with the exception that the coin mechanism is eliminated. 105

The above description relates to what I might call the preferred embodiment of my 110

invention and I wish it understood that I may make such changes in arrangements, combinations and constructions of parts as may fall within the scope of the appended 5 claims.

Having thus described my invention, what I claim as new is:

1. In combination with an air hose of a support consisting of a vertical hollow post, 10 a collar situated upon the top end of said post, standards diametrically opposed and vertically extending from said collar, a lever pivotally mounted between said standards, said lever provided with a handle having a 15 weight at its extremity for normally holding the same in a substantially vertical position, the other end of said lever provided with a hook shaped portion having a slot therein, said hose adapted to extend through 20 said lever.
2. In combination with an air hose of a

support consisting of a vertical hollow post, a collar situated upon the top end of said post, standards vertically extending from and diametrically disposed upon said collar, 25 a hollow lever pivotally mounted between said standards, said lever provided with a handle having a weight at its extremity for normally holding same in a vertical position, the other end of said lever being provided 30 with a hooked portion having a slot therein, an arcuate plate situated adjacent the fulcrum point of said lever and means provided for engaging said arcuate plate for holding said lever in a substantially vertical position. 35

In testimony whereof I affix my signature in presence of two witnesses.

STEAD A. ASQUITH.

Witnesses:

DOROTHY BELLINGHAM,
M. A. BELLINGHAM.
